BRUSH WITH A POLISH HOLDING COMPARTMENT

William Ernest Kendall Waiting, Brackley, England

Application September 20, 1955, Serial No. 38,007

Claims priority, application Great Britain March 29, 1955

Term of patent 14 years

(Cl. D9—2)

Fig. 1.

Fig. 2.

Fig. 3.

Fig. 4.

Fig. 1 is a side elevational view of a brush with a polish holding compartment, showing my new design;

Fig. 2 is an end view thereof taken from the right of Fig. 1;

Fig. 3 is a top plan view, and

Fig. 4 is a perspective view showing the side opposite that shown in Fig. 1.

I claim:

The ornamental design for a brush with a polish holding compartment, as shown.
